UNITED STATES PATENT OFFICE.

GUSTAVUS A. PADDOCK, OF BEAVER DAM, WISCONSIN.

HARNESS-BUCKLE.

SPECIFICATION forming part of Letters Patent No. 436,186, dated September 9, 1890.

Application filed November 23, 1889. Serial No. 831,309. (No model.)

To all whom it may concern:

Be it known that I, GUSTAVUS A. PADDOCK, a citizen of the United States, residing at Beaver Dam, in the county of Dodge and State 5 of Wisconsin, have invented a new and useful Harness-Buckle, of which the following is a specification.

My invention relates to buckles which have shields or guards secured to them; and the 10 objects of my improvement are, first, to provide a shield which cannot be misplaced by accident; second, to prevent any danger of the straps becoming unbuckled by accident; third, to prevent the buckle being drawn 15 through the terret, and, finally, to accomplish all these ends with a light and convenient buckle. Such a buckle is shown in the accompanying drawings, in which—

Figure 1 is a perspective view of the buckle 20 when closed as in use. Fig. 2 is a plan view of the same; Fig. 3, an edgewise view of the buckle when open or partly so; and Fig. 4, an edgewise view of the buckle and straps when 25 in use, the straps in this case spreading apart, as will be the case when this buckle is used to connect the short cross-line to the long one.

Similar letters refer to similar parts throughout the several views.

The buckle-frame consists of the cross-bar 30 B, against which the point of the tongue F rests, the side bars A A, and the clips E E, said clips being clasped around the cross-bar D of the shield D G C.

The shield D G C is composed of the cross- 35 bar C, the cover G, the cross-bar D, around which the tongue F is clasped, and the two side bars which connect the three. It will be seen that there is thus formed a loop between the cross-bar C and the shield G, which opening 40 I will designate as "loop" C.

One point gained by having one pair of cross-bars directly outside the others is that the article is thus so widened that it cannot be drawn through the terret, and thus it will 45 prevent such accidents as often occur on account of the buckle being caught in the terret.

It will be seen that in the construction shown in the drawings the tongue encircles the heel D of the shield and that the heel of

the buckle-frame is divided into two parts E 50 E. This particular construction is not essential, as any form in which the shield is hinged to the buckle-frame and the loop lies outside of the cross-bar, against which the point of the tongue rests, comes within the scope of my 55 invention and accomplishes the main object sought. By the word "heel" I designate, in general, that line on which the tongue is hinged in contradistinction from the end or bar against which the point of the tongue rests. 60

For ordinary use on harness the one strap I is sewed or otherwise secured around the clips E E, and the cross-bar D and the other strap H is first passed through the loop C. Then by opening the buckle, as shown in Fig. 65 3, it is passed through the buckle-frame and between G and D. Then when the tongue F is inserted in the strap the buckle can be closed together, as in Fig. 4, and no accident can unbuckle the strap. 70

I am aware that shield-buckles have been made in which the shield was hinged to the cross-bar corresponding to the cross-bar B in my buckle, said shield being when in use closed down toward the heel of the buckle and 75 having in the end a loop adapted to receive the billet. My buckle differs from this in having the shield close down the other way; also in that the loop of that buckle is adapted to receive only the billet or loose end of the strap, 80 while in my buckle the loop is adapted to receive the other part of the strap as it lies outside of the cross-bar B, instead of inside, as is the case with the other. 85

I claim as my invention—

A buckle-shield hinged to the buckle-frame at a point in the rear of the cross-bar B, against which the point of the tongue rests, said shield being adapted to close outwardly over said cross-bar and provided with a loop C, 90 adapted to receive a strap, said loop lying, when the shield is closed down, in front of the cross-bar B and extending beyond it, substantially as described. 95

GUSTAVUS A. PADDOCK.
